CLAIM

The ornamental design for a cover for a baby support insert, as shown and described.

DESCRIPTION

FIG. 1 is a plan view of the cover for a baby support insert; FIG. 2 is an elevational view of the cover for a baby support insert looking down on the top of FIG. 1;

FIG. 3 is a elevational view of the cover for a baby support insert looking up at the bottom of FIG. 1;

FIG. 4 is a front elevational view of a modified cover for a baby support insert with the hand features untied and illustrating velcro strips;

FIG. 5 is a rear elevational view of the cover for a baby support insert, on an enlarged scale, looking at the rear of FIG. 1; and,

FIG. 6 is a left side elevational view of the cover for a baby support insert, also on an enlarged scale, looking at the left of FIG. 1.
